175,915

FONT OF TYPE

David Schorr, Detroit, Mich.

Application January 26, 1955, Serial No. 34,239

Term of patent 7 years

(Cl. D64—12)

The drawing shows a font of type embodying my new design.

I claim:

The ornamental design of a font of type, substantially as shown.

References Cited in the file of this patent

UNITED STATES PATENTS

D. 1,933 Page _____ Apr. 19, 1864
D. 26,428 Moore _____ Dec. 22, 1896

OTHER REFERENCES

American Type Founders Company, Specimens 1896, page 509, Multiform, #4, 36 point.